(57) **CLAIM**

The ornamental design for a low debris dust cap, as shown and described.

DESCRIPTION

FIG. 1 is a top front right perspective view of a first embodiment of a low debris dust cap showing our new design;

FIG. 2 is a front elevation view thereof, the back side being the same;

FIG. 3 is a right side elevation view thereof, the left side elevation being the same;

FIG. 4 is a top plan view thereof;

FIG. 5 is a bottom plan view thereof;

FIG. 6 is a top front right perspective view of a second embodiment of a low debris dust cap showing our new design;

FIG. 7 is a front elevation view thereof, the back side being the same;

FIG. 8 is a right side elevation view thereof, the left side elevation being the same;

FIG. 9 is a top plan view thereof; and,

FIG. 10 is a bottom plan view thereof.

The broken lines shown in the figures are for the purpose of illustrating portions of the low debris dust cap and form no part of the claimed design.
